(57) **CLAIM**

The ornamental design for a light box wrap, as shown and described.

DESCRIPTION

FIG. 1 is a facing, perspective view of a light box wrap, wherein the break lines within the light box wrap and corresponding bracket represent indeterminate length, and line shading within the break lines represent resin material in cross-section;

FIG. 2 is a front elevational view thereof;

FIG. 3 is a back elevational thereof;

FIG. 4 is a right elevational thereof;

FIG. 5 is a left elevational thereof; and,

FIG. 6 is a top plan view thereof.

The side portions of the light box wrap configured to be placed behind a desk or other structure are unornamented.

The broken lines immediately adjacent the shaded areas represent the bounds of the claimed design, while all other broken lines in the drawings are included for environmental or illustrative purposes only the broken lines form no part of the claimed design.
